[57] CLAIM

I claim the ornamental design for a 'bingo marker', as shown and described.

DESCRIPTION

FIG. 1 is a front elevational view of a bingo marker, showing my new design;

FIG. 2 is a rear view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a top and right front perspective view thereof;

FIG. 8 is a bottom and left rear perspective view thereof;

FIG. 9 is a front elevational view of a second embodiment of the design in FIG. 1;

FIG. 10 is a rear view of FIG. 9;

FIG. 11 is a right side elevational view of FIG. 9;

FIG. 12 is a left side elevational view of FIG. 9;

FIG. 13 is a top plan view of FIG. 9;

FIG. 14 is a bottom plan view of FIG. 9;

FIG. 15 is a top and right front perspective view of FIG. 9;

FIG. 16 is a bottom and left rear perspective view of FIG. 9;

FIG. 17 is a front elevational view of a third embodiment of the design in FIG. 1;

FIG. 18 is a rear view of FIG. 17;

FIG. 19 is a right side elevational view of FIG. 17;

FIG. 20 is a left side elevational view of FIG. 17;

FIG. 21 is a top plan view of FIG. 17;

FIG. 22 is a bottom plan view of FIG. 17;

FIG. 23 is a top and right front perspective view of FIG. 17; and,

FIG. 24 is a bottom and left rear perspective view of FIG. 17.
